LINE COMPOSING AND CASTING MACHINE.

1,108,826.

Specification of Letters Patent. Patented Aug. 25, 1914.

Application filed February 25, 1913. Serial No. 750,615.

To all whom it may concern:

Be it known that I, HENRY A. ARMSTRONG, a citizen of the United States, residing at Brooklyn, in the county of Kings and State 5 of New York, have invented new and useful Improvements in Line Composing and Casting Machines, of which the following is a specification.

This invention relates to improvements in 10 line composing and casting machines and is especially adapted for use in connection with those of the well known linotype class which employ wedge spacers which are introduced into the line during the composition thereof 15 by manipulation of a keyboard.

The primary object of the invention is to provide improved escapement mechanism for controlling the delivery of the spacers from the box or reservoir in which they are 20 stored whereby the spacers will be delivered more promptly in response to manipulation of the keyboard, and greater certainty and efficiency in the control of the spacers is attained.

25 To these and other ends, the invention consists in certain improvements, and combinations and arrangements of parts, all as will be hereinafter more fully described, the novel features being pointed out particularly 30 in the claims at the end of the specification.

In the accompanying drawing:—Figure 1 is a perspective view of a reservoir containing spacers and embodying escapement mechanism constructed in accordance with 35 the present invention, the door being removed for clearness in illustration; Fig. 2 is a perspective view of the door; Fig. 3 represents a vertical section of the delivery end of the reservoir showing the position 40 occupied by the foremost spacers therein.

Similar parts are designated by the same reference characters in the several views.

The present invention is applicable generally to line composing and casting machines of various types and also to spacers of different types. In the present instance, the invention is shown and will be described as applied to a machine of the linotype class and to spacers as generally employed in that 50 class of machines, the general type of machine and spacers being disclosed fully in the patent to Ottmar Mergenthaler, No. 436,532, dated September 16, 1890, and to which reference is made. It may be explained that the wedge spacers, the delivery

of which is controlled by the escapement mechanism embodying the present invention, are commonly employed in machines of the linotype class for the purpose of justifying the composed line and spreading the matrices 50 in the line to fill out the same to standard length, and the spacers as generally used are each composed of two parts having complementary inclined surfaces which are slidable upon one another, thus forming a wedge, the 55 two parts or members of the spacer having a dove-tail connection. These spacers are commonly known as space bars or space bands and they are stored in a space box or reservoir in readiness to be delivered to the assembling line as required by proper manipulation of the keyboard.

In the present embodiment of the invention, the space box or reservoir embodies opposed side members 1 and 2 which are spaced 75 apart to form a passageway between them for the spacers, and the sides of the reservoir are held in proper spaced relation by the connecting screws 3. In the present instance, spacers of the form commonly used 80 are shown, each spacer being composed of a relatively short member 4 and a relatively long slide 5 which depends therefrom, these members having the complementary inclined surfaces and the slidable dove-tail connection as described above and disclosed in the prior patent referred to. The upper member 4 is provided with a pair of outwardly projecting lugs 6 upon which the spacer is adapted to be suspended. The side members 90 1 and 2 of the reservoir are formed with a pair of surfaces 7 which are inclined downwardly toward the delivery end of the reservoir, and the outwardly projecting lugs 6 on the spacers rest on these inclined surfaces 95 and gravitate along the same to the delivery end of the reservoir. A rail 8 is fitted in the upper portion of the reservoir at a point between the side members thereof and is adapted to engage in the correspondingly 100 shaped recesses 9 which are formed in the tops of the members 4 of the spacers. A door or cover plate 10 is provided which serves to normally close the front or delivery end of the reservoir, a screw inserted in the 105 holes 11 and 11^a serving to pivotally connect the door to the reservoir, and another screw 12 is adapted to enter a notch 13 in one side of the door and to clamp the door in its normally closed position, loosening of the screw 110

12, however, permitting the door to be readily swung into open position about the screw in the hole 11 as a center.

A pair of rails 14 and 15 are arranged between the side members 1 and 2 of the reservoir and are adapted to coöperate with the vertical edges of the lower slide members 5 of the spacers contained in the reservoir. A dog 16 is fixed in the passageway for the spacers and in a position to form an abutment or stop for the lower slide member 5 of the foremost spacer in the reservoir, this dog in the present instance being shown attached to the forward or delivery end of the rail 14. That end of the rail 15 toward the delivery end of the reservoir terminates at a point where it will be clear or in rear of the lower slide member 5 of the foremost spacer in the reservoir, and a spring 17 is provided which bears against the adjacent side edge of the lower slide member 5 of the foremost spacer, this spring having a tendency to move inwardly or toward the fixed dog 16. A plunger 18 is mounted in the side member 1 of the reservoir, and its inner end is arranged to bear against the lower slide member 5 of the foremost spacer which rests against the stop 16 as an abutment and is normally retained in engagement therewith by the spring 17. A spring 19 acts normally to withdraw the plunger 18. This plunger is adapted to be actuated by a part having a mechanical connection with an appropriate key on the keyboard whereby actuation of such key will force the plunger 18 inwardly against the action of its retracting spring and will thereby move the lower slide member 5 of the foremost spacer edge-wise and laterally, in opposition to the action of the spring 17, thereby disengaging the same from the dog 16.

A pair of rails 20 and 21 are fitted against the inner sides of the side members 1 and 2, and these rails serve as supports for the shoulders 22 which are formed at the opposite sides of the upper member 4 of each spacer. The rails 20 and 21 terminate in rear of the door 10, thereby forming a passageway for the lugs 6 of the spacers after the latter have been released by the escapement mechanism and drop into the delivery chute 23, as shown in Fig. 3. The dog 16 is also offset to the rear of the forward termini of the rails 20 and 21 whereby the foremost spacer in the reservoir will occupy an inclined position with the upper end thereof tilted forward beyond the surfaces 7 and resting against the door 10, which latter acts as an upper abutment. While the foremost spacer is in this position, the shoulders 22 on the upper member 4 of this spacer will rest on the rails 20 and 21 whereby such spacer will be supported in the position described. However, when the plunger 18 is actuated, the lower slide member 5 of the

foremost spacer will be freed from the dog or lower abutment 16, thereby permitting the lower portion of the spacer to swing forward; and as the spacer approaches an upright or vertical position, the shoulders 22 on the upper member 4 will pass forwardly off of the rails 20 and 21, and this spacer will then be free to drop vertically into the delivery chute 23, as shown by the dotted lines in Fig. 3. When a spacer is delivered from the reservoir in the manner stated, the next succeeding spacer will come against the dog 16 and it will then occupy the same position as that of the preceding spacer.

The spacers are usually introduced into the reservoir at the rear end 24 by distributing mechanism after a cast has been made from the composed line.

Escapement mechanism embodying the present invention is very simple in its construction, and in practice, it is not only reliable as a means for controlling the delivery of the spacers, but it will be observed that each spacer begins to descend the moment it is released, thereby insuring more prompt delivery of the spacers as compared with escapement mechanisms as heretofore used wherein the spacers are raised or lifted during the releasing operation, and such lifting or raising of the spacers occasions a slight delay or lag in the delivery of the spacers in response to operation of the keyboard, requiring the operator to pause to insure introduction of the spacer into the line at the proper point. Another objection to an escapement mechanism which involves lifting or raising of the spacer incident to the releasing thereof is that congestion of the spacers occurs frequently owing to the fact that more than one spacer would be lifted before the spacer which it was intended to release had dropped clear of the spacers following it. Interference between the spacers is impossible with the present invention owing to the inclined position occupied by the foremost spacer, this spacer when released having ample room in which to drop before the following spacer can be released.

I claim as my invention:

1. In a machine of the class described, escapement mechanism for spacers embodying upper and lower abutments, spacer-supporting devices located between the upper and lower abutments, and means for moving the spacer laterally to release it from the lower abutment.

2. In a machine of the class described, escapement mechanism for spacers embodying upper and lower abutments against which a spacer is adapted to rest, means located below the upper abutment for supporting the spacer while the latter rests against said abutments, and means for deflecting the spacer laterally to release it from the lower abutment whereby the spacer will

assume a position which will free it from said supporting means.

3. In a machine of the linotype class, a spacer-controlling escapement consisting of 5 upper and lower abutments adapted to detain the spacer from advancing, a supporting ledge below the upper abutment adapted to prevent the spacer from falling, and means for moving the spacer laterally to 10 release it from its lower abutment whereby the lower end of the spacer may advance and thus allow the supported part to clear the ledge.

4. In a machine of the class described, 15 spacer-controlling escapement mechanism embodying means for holding the spacer in inclined position, means for supporting the spacer while occupying such position, and means for moving the spacer laterally 20 whereby it may approach an upright position and thereby disengage from said supporting means.

5. In a machine of the class described, 25 spacer-controlling escapement mechanism embodying vertically spaced devices coöperative to hold a spacer in inclined position, a ledge arranged between said devices and operative to support the spacer while held by said devices, and means for moving the

spacer laterally to release it from the lower 30 of said holding devices whereby the spacer may move toward an upright position and thereby free itself from said supporting ledge.

6. In a machine of the linotype class, the 35 space band magazine or reservoir, and a spacer-controlling escapement for releasing the leading spacer from the magazine at will, said escapement consisting of an abutment for the upper end of the spacer to rest 40 against, a dog to hold back the lower end of the spacer so that the spacer will have a backward inclination, a rail to support a shoulder of the spacer located intermediately of said abutment and detent, and 45 means for moving the spacer laterally to release it from said dog whereby the spacer may swing toward the delivery end of the magazine, clear of the supporting rail, and thus be released without lifting. 50

In testimony whereof I have hereunto set my hand in presence of two subscribing witnesses.

HENRY A. ARMSTRONG.
